United States Patent Office

Des. 194,246
Patented Dec. 18, 1962

194,246

PACKAGE, OR SIMILAR ARTICLE

James A. Engelmann, La Canada, Calif., assignor to Bras of Hollywood-West, Inc., Los Angeles, Calif., a corporation of California

Filed Mar. 5, 1962, Ser. No. 69,065

Term of Patent 14 years

(Cl. D58—12)

FIG. 1.

FIG. 2.

FIG. 3.

FIG. 4.

FIG. 5.

FIG. 1 is a front perspective view of a package, or similar article, showing my new design;

FIG. 2 is a front elevational view thereof;

FIG. 3 is a side elevational view thereof;

FIG. 4 is a rear elevational view thereof; and

FIG. 5 is a cross-sectional view thereof taken on line
5—5 of FIG. 2.

I claim:

The ornamental design for a package, or similar article,
substantially as shown.
